VIBRATORY IMPULSE GENERATOR FOR GOLF CLUB

Louis G. La Ferte, Santa Cruz, Calif.

Application February 16, 1956, Serial No. 565,874

6 Claims. (Cl. 273—186)

The present invention relates to a golf club, and pertains more particularly to a practice golf club having vibratory means mounted in the head thereof for emphasizing the location of the club relative to a user by impulses transmitted by the vibratory means.

It is well known that when a steady sensory impulse, such as pressure, is applied to a person's skin, unless the pressure is sufficient to cause pain, the perception of the pressure by the brain is soon compensated for and after a few moments is not felt as keenly as when first applied. On the other hand, any variation in the impulse will be immediately sensed, and for this reason a vibratory impulse of a predetermined magnitude will be sensed keenly much longer than a steady impulse of the same maximum magnitude.

In golf instruction, whether teaching the rudiments to a beginner or correcting a fault of an experienced player, the teacher, or "professional" as he is called, usually has his greatest difficulty in making the pupil understand what he, the pupil, is doing wrong. However, the understanding of his error is almost a necessary precedent in teaching the pupil how to do it right.

One reason that the pupil is unable to realize what he is doing wrong is because, after he has gripped the club with a steady pressure for a few moments he is unable to fully feel the club, and thereby sense its position relative to his body.

An object of the present invention is to make an improved golf club for use in making practice swings.

Another object is to provide a golf club with means for creating a vibratory impulse capable of being sensed by a person swinging the club.

A further object of the invention is to provide a practice swing golf club head with vibratory means, and drive means for actuating the vibratory means during a swing of the club for transmitting a pulsating impulse to a person swinging the club.

Another object of the invention is to provide vibratory means in a golf club head which will transmit vibrations along the club shaft to a user's hands, and will also transmit sound waves audible to the user during a practice swing.

These and other objects of the invention will be apparent from the following description and the accompanying drawings, wherein:

Fig. 1 is an elevational view of the impact or striking face side of a golf club head in which is mounted a weight actuated vibratory mechanism embodying the invention, said vibratory mechanism being shown somewhat diagrammatically in dotted lines.

Fig. 2 is a view similar to Fig. 1 but showing the vibratory mechanism of Fig. 1 mounted to extend lengthwise from front to rear of the club head.

Fig. 3 is an enlarged longitudinal median sectional view showing the vibratory mechanism illustrated in Figs. 1 and 2.

Fig. 4 is a sectional view taken along line 4—4 of Fig. 3.

2

Fig. 5 is a transverse sectional view taken along line 5—5 of Fig. 4.

Fig. 6 is a similar sectional view taken along line 6—6 of Fig. 4.

5 Fig. 7 is a similar view taken along line 7—7 of Fig. 4. Fig. 8 is a longitudinal sectional view taken along line 8—8 of Fig. 3.

10 Fig. 9 is a sectional view through a golf club head taken in a plane at right angles to both the club face and club bottom, and showing a modified form of vibratory mechanism.

In Fig. 1 a generally conventional type of golf club head A of the "wood" type has a cylindrical cavity 10 formed therein with its axis perpendicular to the sole 11 or base of the club head and approximately at the center of balance of the club head. In this cavity 10 is fitted a weight actuated vibratory mechanism B (Figs. 3 to 8 inclusive) comprising a tubular casing 12 in which a weight 13 is mounted for slidable movement along a rotatable shaft 14 which is provided with helical vanes 15 which fit into corresponding grooves 17 in the weight so that as the weight is moved lengthwise of the shaft 14 it will produce a relative rotative movement between the weight and the shaft.

20 The weight 13 is retained from rotative movement about the axis of the shaft 14 by a pair of lengthwise extending guide tracks 19 and 20 attached to the interior of the casing 12 in a diametrically opposite relation. The weight is notched out at 21 and 22 to receive the tracks

25 19 and 20 respectively in slidably interfitting relation. A gear-like member 23 is secured to the shaft 14 near its lower end to vibrate a pair of wire spring members 27 and 28. The lower end portions 29 of the springs 27 and 28 are arranged to ride along the upper sides of the teeth 30 of the member 23 during a practice swing of a club in which the device B is mounted, to produce vibrations which will be transmitted through the club shaft to the hands of the person holding it, and will also produce sounds which will help the user audibly follow the club head during a practice swing.

30 The tubular casing 12 may be of metal or plastic tubing, and has a pair of end closure disks 31 and 32 screwed into internally threaded end portions 33 and 34 of the casing 12. The end closure disks 31 and 32 are provided with central recesses 37 and 38 respectively to 35 provide journal support for the rotary shaft 14.

35 Each of the springs 27 and 28 consists of a helically coiled portion 39 mounted loosely to encircle one of a pair of studs 40 mounted to project radially inwardly from opposite sides of the casing 12 at an angle of 90° from 40 the centers of the guide tracks 19 and 20.

45 Each upwardly projecting spring portion passes between a pair of parallel guide wires 43 and 44 which are secured to extend transversely of the casing at right angles to the common axes of the spring support studs 40 to guide 50 the upwardly projecting spring portions 27 when the latter are being caused to vibrate by the lower spring portions 29 passing across the teeth 30 of the gear-like member 23.

55 The upper end of each upwardly projecting spring portion 27 is curled to form a ring-like portion 45 to act as a hammer for striking a pair of arcuate anvils or striking blocks 47 and 48, one of which is mounted on each side of the casing 12 near its upper end and in the path of movement of the upper end rings 45.

60 The sides of the weight 13 are cut away at 49 and 50 so as to clear the spring supporting studs 40 when the weight moves back and forth along the tracks 19 and 20. When the club head A with the device B mounted therein as shown in Fig. 1 is raised overhead on the top of a 65 swing to an inverted position from that shown in Fig. 1, the weight 13 will tend to gravitate downwardly along

the inverted shaft 14, turning the latter by means of the helical vanes 15 riding in the grooves 17.

In order to facilitate the downward gravitation of the weight 13 when the club head is thus inverted, the helical portions 19 of the springs 17 and 18 may be made sufficiently loose on their respective supporting studs 40 that when the club head is thus inverted at the top of a swing, the loosely fitted helical portions 39 will allow the entire springs 27 and 28 to drop downwardly sufficiently so that the end portions 41 will clear the teeth 30, permitting the gear-like member 23 to rotate freely.

As the centrifugal force generated by the downward swing of the club causes the weight 13 to force its way outwardly along the shaft 14, thereby turning it, the springs 17 and 18 likewise will be forced outwardly by the same centrifugal force, so as to again bring the end portions 41 of the springs into contact with teeth 30 and thus will provide the desired vibratory impulse to vibrate the upper end portions 42 of the springs against the impact blocks 47 and 48. The engagement of the spring ends 41 with the teeth 30 tends to retard the rotation of the gear-like member 23, so that the vibratory period of the device will thus be lengthened so as to endure throughout at least a major portion of the club swing.

In the arrangement shown in Fig. 2, the same vibratory mechanism B may be used, but is mounted so that the axis of the rotary shaft 14 is disposed perpendicularly to the striking face 50 of a club head C. When thus arranged, the weight 13 will be moved along the shaft 14 to create the vibratory impulses in the manner described previously herein by variations in the acceleration of the club head. This will teach the pupil using the club when he is accelerating and when he is not, a very important factor in some phases of golf instruction.

Regardless, however, of whether the device B is mounted as shown in Fig. 1 or in Fig. 2, the vibratory impulses which it generates during a practice swing of the club makes the user actuatedly aware of the position of the club relative to his hands and body. Both of these arrangements shown in Figs. 1 and 2 may be provided in alternate clubs, so that when an instructor is attempting to teach a student how and when to accelerate the club head he may use the form shown in Fig. 2, while in teaching some other phase of the swing he may prefer to employ a club of the type shown in Fig. 1.

In the modified form of the invention shown in Fig. 9, a small conventional clockworks or electrically energized motor (not shown) is mounted in a casing 51 which, in turn, is mounted in a cavity 52 provided therefor in a club head D. If a clockworks is used, a winding shaft 53 may be exposed through a hole 54 in the rear of the club to receive a usual winding key, not shown.

Suitable control means such as an electric control circuit (not shown) may be connected to the motor in the casing 51 by electric conductors 57 so that the motor may be started and stopped at desired intervals either by the pupil or by the instructor. The motor may be of any of a number of well known types which will produce a vibratory signal during their operation. Such motors are well known, and form no part of the present invention.

The device comprises a simple, inexpensive and easily operated device which assists a golf instructor by providing means for indicating to a pupil the relative positions of the golf club with respect to his hands and other parts of his body which is impossible of full perception when the club is static.

When the proper swing has been achieved, and has been practiced sufficiently with a practice club embodying the present invention to become a habit, then the practice club is set aside and the pupil is ready to play golf or to practice actually hitting a ball with his regular clubs.

While I have illustrated and described a preferred embodiment of the present invention, it will be understood, however, that various changes and modifications may be made in the details thereof without departing from the

spirit and scope of the invention as set forth in the appended claims.

Having thus described the invention, what I claim as new and desire to protect by Letters Patent is defined in the following claims.

I claim:

1. In combination with a golf club comprising a shaft and a head thereon, a vibrator mechanism mounted in the head and capable of transmitting sensibly perceptible vibrations along the club shaft to the hands of a person gripping the club, and driving means for actuating the vibrator during a predetermined swing of the club.

2. In combination with a golf club comprising a shaft, and a head thereon, a vibrator mechanism mounted in said head and comprising an inertia element slidably mounted for movement in the direction of club head movement during a swing of the club, a shaft rotatably mounted in the vibrator mechanism, driving means interconnecting the inertia element and the shaft, and vibrator means actuated by the shaft for transmitting sound waves to the air and sensibly perceptible vibrations along the shaft to the hands of a person gripping said shaft.

3. In combination with a golf club comprising a shaft and a head thereon, a vibrator mechanism mounted in the head and comprising a body, an inertia element slidably mounted in the body for movement in the direction of club head movement during a swing of the club, a shaft rotatably mounted in the body, helical threads interconnecting the inertia element and the shaft, a toothed wheel rotatably driven by the shaft, and a vibrator reed connected to the body and positioned for engagement by the toothed portion of the toothed wheel upon a rotation of the latter, thereby to transmit sensibly perceptible vibrations along the club shaft to the hands of a person gripping the club during a predetermined accelerative swing of the club.

4. In combination with a golf club comprising a shaft and a head thereon, a vibrator mechanism mounted on the head and comprising a body, an inertia element slidably mounted in the body for a movement in the direction of club head movement during a swing of the club, a shaft rotatably mounted in the body, helical threads interconnecting the inertia element and the shaft, a toothed wheel driven by the shaft, a pivotal mounting fixed to the body, an anvil fixed to the body, and a vibrator reed operably engaging the mounting and having one portion engaging the toothed portion of the toothed wheel and another portion striking the anvil, thereby to transmit sensibly perceptible vibrations along the club shaft to the hands of a person gripping the shaft during a predetermined accelerative swing of the club.

5. In combination with a golf club comprising a shaft and a head thereon, a vibrator mechanism mounted on said head and comprising a body, an inertia element slidably mounted in the body for movement in the direction of club head movement during a swing of the club, a shaft rotatably mounted in the body, helical threads interconnecting the inertia element and the shaft, a toothed wheel driven by the shaft, a pivotal mounting fixed to the body, an anvil fixed to the body, a vibrator reed operably engaging the mounting and having one portion engaging the toothed portion of the toothed wheel and another portion striking the anvil, and spatially disposed guides for the reed adjacent the anvil, whereby, upon a predetermined accelerative swing of the club, the inertia element is moved to actuate the rotatable shaft and the toothed wheel, which in turn vibrates the reed and transmits sensibly perceptible vibrations from the anvil along the club shaft to the hands of a person gripping the shaft.

6. In combination with a golf club comprising a shaft and a head thereon, a vibrator mechanism on the club head comprising a body, an inertia element slidably mounted in the body for movement in the direction of club head movement during a swing of the club, a shaft rotatably mounted in the body, helical threads intercon-

necting the inertia element and the shaft, a toothed wheel driven by the shaft, a pivotal mounting fixed to the body, an anvil fixed to the body, a vibrator reed operably engaging the mounting and having one portion engaging the toothed portion of the toothed wheel and another striking the anvil, and differentially roughened guides for the reed adjacent the anvil, whereby, upon a predetermined accelerative swing of the club, the inertia element is moved to actuate the rotatable shaft and the toothed wheel, which

in turn vibrate the reed and transmit sensibly perceptible vibrations from the anvil along the club shaft to the hands of a person gripping the shaft.
